UNITED STATES PATENT OFFICE.

WILLIAM E. PRICE, OF WHITE PLAINS, NEW YORK.

METHOD AND APPARATUS FOR MAKING DISPLAY SIGNS, LAMP SHADES, AND OTHER LIKE ARTICLES.

Application filed April 30, 1926. Serial No. 105,664.

This invention relates to a method and an apparatus for making display signs, lamp shades, and other like articles.

In my co-pending applications Serial No. 5 60,159, filed October 3, 1925, I have shown and described a sign or like ornament in which a fabric is drawn through a perforated sheet to provide the legend or ornamentation. The object of this invention is to provide a 10 simple and highly efficient method and apparatus for applying the fabric to and drawing it through the perforated sheet, and assembling the various elements to form the complete sign.

15 Other objects of this invention will in part be obvious and in part hereinafter pointed out.

Certain features herein shown and described are shown, described and claimed in 20 my aforementioned co-pending application, the present application being a continuation of said application.

With the above exception, the invention accordingly consists in the features of construction, combinations of elements and arrangement of parts which will be exemplified in the construction hereinafter described, and of which the scope of application will be indicated in the following claims.

25 30 In the accompanying drawing, in which is shown one of the various possible illustrative embodiments of this invention,

Fig. 1 is a side elevational view, partly in section, of an apparatus for carrying out the 35 improved method embodying the invention.

Fig. 2 is a plan view thereof, and

Fig. 3 is an enlarged fragmentary cross sectional view taken on lines 3—3 in Fig. 2.

Referring in detail to the drawing, 10 denotes an apparatus for carrying out the improved method embodying the invention, said 40 method being here described as applied to assembling electrically illuminated sign 30 such as described in detail in my aforementioned co-pending application.

The apparatus 10 is seen to comprise a suction box 11 supported at a suitable height on legs 12. The bottom 11^a of the box communicates through a pipe 12 with the intake 50 13^a of a blower 13, said blower being driven in any suitable manner as by being directly connected to an electric motor 14. Said blower and motor are preferably mounted on a platform 15 as shown in Fig. 1.

55 Suitably supported from side 11^b of the box

11, below the top thereof, is mounted a lamp socket 16 having the bulb 17, said socket 16 and motor 14 being connected through wires 18 to a suitable electric supply source (not shown).

The box 11 may be formed of wood, sheet metal or other suitable material and may have the top side provided with a mounting means, such as a frame 19 having a central opening 19^a, said frame being adapted to 60 support the legend plate 20 of the sign 30 to be assembled. Said legend plate may be formed of a relatively stiff backing material such as sheet metal, fibre, composition or other similar material, and has a desired legend 65 20^a of plain or intricate configuration in the form of letters, symbols or ornamentations cut in perforated outline or stencil through said sheet in any well-understood manner.

The sign 30 to be assembled, comprises a 70 75 flexible fabric 22 associated with perforated plate 20, and one of the dominant features of this invention resides in the provision of an improved method of assembling said plate and fabric so as to quickly and evenly project portions 22^a of the fabric through said 80 perforated plate so as to require little care or skill of manipulation.

In carrying out the improved method, the legend plate 20 is positioned with the front 85 face down over the frame opening 19^a as shown in Figs. 1 and 3, then a strip of flexible fabric preferably a textile fabric 22, such as China silk, is superimposed on the back side of said plate. (See Fig. 1.) Power is now 90 applied to operate the motor 14 and blower 13, and to light the bulb 17. The operation of the blower exhausts the air from the casing 11, creating a suction which draws the portions of the fabric 22 through the perforated 95 legend 20^a for quickly and evenly projecting portions of the strip through said plate, thus forming raised or embossed protuberances 22^a, the intaglio surfaces of which extend out from the front side of said plate as shown in 100 Fig. 3. While the suction applied to the front side of the plate 20 retains the strip 22 and the protuberances 22^a in a proper assembled position, a suitable adhesive coating such as sodium silicate, shellac, varnish, lacquer or 105 other like substance is applied for fixedly securing the strip 22 to said plate 20. When the material used for the strip 22 is porous, as for example, China silk, the air sucked through the strip will aid in distributing and drying 110

the adhesive coating applied thereto. Thus the strip 22 is not only cemented to the plate by the adhesive coating but this coating is also effective to stiffen the protuberances 22 for retaining them in proper shape, said protuberances then forming what is commonly termed an "unbreakable structure" which is highly efficient as a light diffusing medium because of its texture. If desired, one or more additional transparent coatings may be applied to the assembled sign as by spraying, to serve as a finishing and protecting means.

The bulb 17 serves not only to illuminate the interior of the casing to facilitate the inspection of the assembling operation but also may serve to supply heat by convection and radiation for quickening the drying and setting action of the adhesive used.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. The art of making a sign or like article consisting in superimposing a flexible sheet of material on one side of a perforated plate, and applying sufficient suction to the other side of said plate to cause portions of said material over plate perforations to be drawn therethrough whereby raised protuberances are formed.

2. The art of making a sign or like article consisting in superimposing a flexible sheet of material on one side of a stencil-cut plate, applying sufficient suction to the other side of said plate to cause portions of said material adjacent the cut portions of the plate to be drawn therethrough whereby raised protuberances are formed, and then fixing the relation of the material and the protuberances with respect to the plate while the suction is effective.

3. The art of making a sign or like article consisting in overlaying one side of a plate having perforations therein with a strip of flexible material, and varying the relative pressures on the opposite sides of said plate to cause projection of portions of said strip through the perforations whereby intaglio surfaces are formed.

4. The art of making a sign or like article consisting in overlaying one side of a plate having perforations therein with a strip of flexible material, varying the relative pressures on the opposite sides of said plate to

cause projection of portions of said strip through the perforations whereby intaglio surfaces are formed; and then applying an adhesive for securing said intaglio surfaces in a set position.

5. The art of making a sign or like article consisting in superimposing a flexible porous sheet of material on one side of a perforated plate, and drawing air through the portion of the material over the plate perforations for causing said portions to be projected through said perforations.

6. The art of making a sign or like article consisting in superimposing a flexible porous sheet of material on one side of a perforated plate, drawing air through the portion of the material over the plate perforations for causing said portions to be projected through said perforations, adhesively securing the material to the plate, and stiffening the material portions in its projected shape for retaining same in shape.

7. The art of making a sign or like article consisting in placing a flexible material against one side of a perforated plate and increasing the pressure on the exposed side of the material relative to that on the opposite side of the plate for projecting portions of the material through the perforations to extend beyond the said opposite side of the plate to form a raised structure.

8. The art of making a sign or like article consisting in placing a flexible material against one side of a perforated plate, increasing the pressure on the exposed side of the material for projecting portions of the material through the perforations to extend beyond the said opposite side of the plate to form a raised structure, cementing said structure to the plate, and simultaneously stiffening said structure to retain same in shape.

9. The art of making a sign or like article consisting in placing a flexible porous sheet against one side of a perforated plate, increasing the relative air pressure on the exposed side of the sheet sufficiently to draw air through the portions of the sheet over the plate perforations for projecting said portions through the perforations to form a structure on said opposite side of plate, and securing said sheet and raised structure to the plate while said increase of pressure is effected.

10. The art of making a sign or like article consisting in superimposing a flexible porous sheet on one side of a perforated plate, drawing air under sufficient pressure through the portions of the sheet over the plate perforations for causing said portions to be projected through said perforations to form a raised structure on the other side of said plate, and distributing an adhesive stiffening coating over said sheet and raised portions.

11. The art of making a sign or like article consisting in superimposing a flexible porous

sheet on one side of a perforated plate, drawing air under sufficient pressure through the portions of the sheet over the plate perforations for causing said portions to be projected through said perforations to form a raised structure on the other side of said plate, distributing an adhesive stiffening coating over said sheet and raised portions, and simultaneously heating the coated portions of the sheet.

12. An apparatus of the character described comprising a box having an opening on which a perforated plate and flexible strip to be assembled is adapted to be mounted, said plate and strip forming a closure for said opening, and suction means for reducing the air pressure inside said box, whereby portions of the strip are projected through said perforated plate.

13. An apparatus of the character described comprising a box having an opening on which a perforated plate and flexible strip to be assembled is adapted to be mounted, said plate and strip forming a closure for said opening, suction means for reducing the air pressure inside said box, whereby portions of the strip are projected through said perforated plate, and illuminating means positioned in the box.

14. An apparatus of the character described comprising a box having an opening on which a perforated plate and flexible strip to be assembled is adapted to be mounted, said plate and strip forming a closure for said opening, suction means for reducing air pressure inside said box, whereby portions of the strip are projected through said perforated plate, means for illuminating the assembled operation positioned in the box and for applying heat for the assembly operation mounted in the box.

15. An apparatus of the character de-

scribed comprising a box, a frame having an opening forming one side of the box adapted to support sign parts for assembling, said parts forming a closure for said opening, and means communicating with the box other than through said opening for unbalancing the air pressure exerted on opposite sides of said parts at said opening for bringing said sign parts into proper assembly.

16. An apparatus of the character described comprising a box having an opening adapted to support sign parts for assembling, said parts forming a closure for said opening, means communicating with the box other than through said opening for unbalancing the air pressure exerted on opposite sides of said parts at said opening for bringing said sign parts into proper assembly, and means mounted in said box for illuminating said opening.

17. An apparatus of the character described comprising a box having an opening adapted to support sign parts for assembling, said parts forming a closure for said opening, means communicating with the box for unbalancing the air pressure exerted on opposite sides of said parts at said opening for bringing said sign parts into proper assembly, and heating means for the assembling operation mounted in the box.

18. In an apparatus for making signs or like articles of the character described, the combination of a perforated plate, a fabric overlying said plate, and means for creating a difference of air pressure between the two sides of said plate for drawing the fabric through said perforations to form protuberances as and for the purpose described and specified.

In testimony whereof I affix my signature.

WILLIAM E. PRICE.
